(57) **CLAIM**

The ornamental design for a glove portion with keyboard adapted to receive a device, as shown and described.

DESCRIPTION

FIG. 1 is a front perspective view of an exemplary embodiment of a glove portion with keyboard adapted to receive a device, in a closed position, showing the new design;

FIG. 2 is a front perspective view of the embodiment, in the open position, thereof;

FIG. 3 is a top plan view of the embodiment, in the open position, thereof;

FIG. 4 is a bottom plan view of the embodiment thereof;

FIG. 5 is a lateral side elevation view of the embodiment thereof;

FIG. 6 is the medial side elevation view of the embodiment thereof;

FIG. 7 is the front elevation view of the finger-end portion of the embodiment thereof; and,

FIG. 8 is an elevation view of an open wrist end portion of the embodiment thereof.

In all figures, any showing of the environment and/or drawing disclosure and/or device and/or key letters by broken lines is for illustrative purposes only and forms no part of the claimed design.

1 Claim, 6 Drawing Sheets
